BY
ATTORNEY

UNITED STATES PATENT OFFICE.

GEORGE H. MARTIN, OF NEW YORK, N. Y., AND ALBERT V. ARNOLD, OF DENVILLE, NEW JERSEY.

GUN.

Application filed November 7, 1921. Serial No. 513,267.

To all whom it may concern:

Be it known that we, GEORGE H. MARTIN, a citizen of the United States, and a resident of New York, county and State of New York, and ALBERT V. ARNOLD, a citizen of the United States, and a resident of Denville, Morris County, State of New Jersey, have invented certain new and useful Improvements in Guns, of which the following 10 is a specification.

This invention relates to guns and particularly to shoulder pad constructions.

One of the objects of the invention is to provide means for varying the angle of departure or "pitch" angle of a gun in such a manner that the pitch may be changed from straight to either plus or minus pitch.

Another object of the invention is to provide means whereby the "balance" of the 20 gun may be varied or adjusted.

Another object of the invention is to provide means whereby the range of the gun may be increased or decreased.

Another object of the invention is to provide a gun having a stock constructed and arranged to facilitate the handling and correct positioning of the gun.

Another object of the invention is to reduce to a minimum the sudden upward or 30 downward throw of the gun barrel when "making" a target.

Another object of the invention is to provide adjustable means for taking up a recoil of a gun.

Further objects will appear from the following description taken in connection with the drawings which form a part of this application and in which

Fig. 1 is an elevation of the butt end of 40 a gun stock having a shoulder pad adjustably secured thereto and constructed in accordance with the invention.

Fig. 2 is a plan view, partly in section, 45 of the butt end of the gun with the base plate and pivoted pad for the adjustable attachment secured thereto, the pad not being shown in this view, and

Fig. 3 is a sectional elevation, broken away, of the gun butt and attachment.

The invention may be briefly described as 50 an attachment for gun stocks comprising two relatively adjustable members so constructed and connected that one member may be swung pivotally with respect to the other

member, means being provided for positively 55 retaining the members in adjusted position.

The shoulder pad is adapted for use in connection with any type of gun such as a rifle, field, trap or shot gun and is so constructed that it may be attached to the body 60 of an ordinary gun stock.

In the drawings there is illustrated a body 10 of a gun stock having secured thereto a base plate 11 to which is attached a pad hereinafter described. In the particular embodiment shown, the base plate 11 is secured to the body of the stock by means of screws 12 which pass through openings formed in the plate.

The base plate 11 has formed thereon at 70 the lateral edges thereof upwardly extending flanges 13 having semi-cylindrical bearings 14 formed therein. The base plate also has an upwardly extending lug 15 disposed between the bearing recesses 14 and has a 75 transverse aperture 16 formed therein for the receipt of a pivot pin as hereinafter described.

The shoulder pad comprises a body portion or cap 17 having longitudinal flanges 80 18 similar to the flanges 13 on the base plate 11. The cap also has a centrally disposed depression between the flanges for receiving the upwardly extending lug 15 carried by the base plate. The flanges 13 have formed 85 thereon semi-cylindrical bearing portions 19 which are adapted to be positioned in the bearing recesses 14 formed in the flanges 13.

A pivot pin 20 extends through the bearings 19 and through the lug 15 whereby the 90 cap or body member 17 may be pivotally oscillated or adjusted.

In order to adjust the shoulder pad and to retain the body in adjusted position, a pair of pins 21 are threaded into bosses 22 95 formed on the base plate and suitably threaded to receive the pins. On their free ends the pins are provided with hemi-spherical heads 23 positioned in alignment with and adapted to be received by hemi-spherical sockets 24 100 formed in the cap or body member 17. In order to facilitate the rotation of the pins 21, each pin is provided with a cross pin or lever 25. A lock nut 21' is carried by the threaded portion of each pin 21 and retains 105 the pin against turning and in adjusted position.

In order to cushion the recoil, the body

- member or cap 17 preferably has secured thereto a cushioning member 26 which may be formed of any suitable flexible or resilient material such as rubber or sponge rubber.
- 5 In the drawings there is shown an intermediate member or shim 27 between the cap 17 and the pad or cushion 26.
- It is believed that the operation of the attachment will be clear from the preceding 10 description but it may be briefly described as follows.
- When the user of a gun desires to elevate the barrel the adjustment pin 21 on one side of the pivot 20 will be rotated in one direction and the adjustment pin on the other side of the pivot will be rotated in the opposite direction. It is assumed, of course, that the lock nuts 21' have been previously loosened. This will swing the shoulder pad 20 about its pivot 20 and the pins will positively hold the pad in adjusted position. In this manner, therefore, the pitch of the gun may be varied at will. As above stated, the recoil will be taken up by the cushion 26.
- 25 Although one specific embodiment of the invention has been illustrated and described, it will be understood that the invention is capable of modification and that changes in the construction and in the arrangement of 30 the various cooperating parts may be made without departing from the spirit or scope of the invention as expressed in the following claims.

What we claim is:

- 35 1. In a gun, a solid stock, a shoulder pad pivoted thereto on a transverse pivot located back of said stock and means disposed on opposite sides of the pivot for bodily adjusting the pad with respect to the stock and 40 retaining the pad in adjusted position.
2. An attachment for gun stocks, comprising a base-plate arranged to be rigidly affixed to the rear end of a gun stock and having bearing parts, a shoulder pad pivoted to said base-plate and having bearing parts coacting with the bearing parts on said base-plate and means disposed on opposite sides of the bearing parts for bodily adjusting said shoulder pad pivotally on the 45 base-plate.
3. An attachment for gun stocks comprising a base plate having bearing parts, a shoulder pad pivoted to said plate and having bearing parts co-acting with the parts on said plate and means on opposite sides of the pivot for adjusting said pad, pivotally, on the base plate.

4. An attachment for gun stocks comprising a base plate having bearing parts, a shoulder pad body member pivoted to said plate and having bearing parts co-acting with the parts on said plate and means on one of the pivotally connected members having a spherical bearing on the other member for adjusting said body member, pivotally, 60 on the base plate.

5. An attachment for gun stocks comprising a member adapted to be rigidly secured to the stock, a member pivoted intermediate its ends to said first named member, and screw threaded adjustable pins mounted on one of and disposed between the pivotally connected members and engageable with the other member for bodily adjusting one of 70 the members on the other.

6. An attachment for gun stocks comprising a member adapted to be rigidly secured to the stock, a member pivoted intermediate its ends to said first named member, and screw threaded adjustable pins mounted on one of and disposed between the pivotally connected members and having a spherical bearing on the other member for bodily adjusting one of the members on the other. 80

7. An attachment for gun stocks comprising a member adapted to be rigidly secured to the stock, a member pivoted intermediate its ends to said first named member, and adjustable pins mounted on one of and disposed between the pivotally connected members and having a spherical bearing on the other member for adjusting one of the members on the other. 85

8. An attachment for gun stocks comprising a base-plate arranged to be rigidly affixed to the rear end of a solid stock and having a bearing part at substantially the center thereof, a shoulder pad having bearing parts at substantially its center coacting with the bearing parts on said base-plate, and a transverse pivot connecting the bearing parts of the base-plate and of the shoulder pad, and screw threaded means disposed on opposite sides of the pivot for bodily adjusting said shoulder pad, said means co-operating with each other to retain the shoulder pad in adjusted position. 95

In witness whereof, I have hereunto set my hand this 3rd day of November, 1921.

GEORGE H. MARTIN. 100

In witness whereof, I have hereunto set my hand this 1st day of October, 1921.

ALBERT V. ARNOLD. 110
